TELEGRAPH TRANSMITTER

Charles W. Winter, Jr., Coconut Grove, Fla., assignor to Pan American Airways Corporation, Jersey City, N. J., a corporation of Delaware

Application April 8, 1937, Serial No. 135,609

6 Claims. (Cl. 178—66)

My invention relates to radio telegraph transmitters and more particularly to an improved circuit for operating transmitters aboard aircraft in such a manner that the frequency of the transmitted signals does not vary during relatively short time intervals.

In various tests which I have made, I have found that when radio telegraph transmitters of the master oscillator-power amplifier type are operated aboard aircraft with conventional type voltage supply circuits, an appreciable "chirp" is present in the emitted signals. The word "chirp", as used herein, indicates the action or character of signals whose transmitted frequency varies during a relatively short time interval, for example, the time interval required for transmitting a dot or a dash.

Signals that "chirp" are difficult to copy due to the fact that the beat note in the receiving head set starts at one frequency when the signal, e. g., a dot or dash, begins and is at an audibly different frequency at the end of the signal.

An object of my invention is to provide a radio telegraphic transmitter for aircraft that will transmit signals whose frequency will not vary during relatively short time intervals.

Another object of my invention is to provide filament compensating means in the voltage supply circuit of a master oscillator-power amplifier transmitter to prevent "chirping" of the transmitted signals.

In accordance with the present invention, I have found that radio telegraphic transmitters suitable for use aboard aircraft may be operated to transmit signals free of "chirping" by properly regulating the amount of voltage applied to the filament of the vacuum tubes in the transmitter. This method has been found more satisfactory than applying the control in the plate circuit which involves careful insulation in the resistances and inductances against high voltage breakdown.

The novel features of my invention are set forth with particularity in the appended claims. The invention itself, however, both as to organization and method of operation may be easily understood from the following description taken in conjunction with the accompanying drawing, which illustrates one non-limiting embodiment of my invention.

Referring now to the drawing, which is primarily a wiring diagram of the transmitter of my invention, the transmitter comprises vacuum tubes 10 and 11 having filaments 12. The vacuum tube 10 is the master-oscillator and the vacuum tube 11

is the power-amplifier. Connected in series with the filaments 12 is a variable resistor 13 and connected electrically in shunt with this resistor is a make and break switch 14 controlled by keying relay 15 which is in turn controlled by a telegraph key 16.

For the sake of simplicity, the grid and plate electrodes of the vacuum tubes 10 and 11 have been omitted, the filaments being the only tube electrodes shown since they are of primary importance in the present invention. The tubes 10 and 11 may be of conventional type and may have any desired number of grid and plate electrodes.

The voltage that is applied during operation of the transmitter to the plate electrodes of the tubes 10 and 11 is obtained from a dynamotor illustrated diagrammatically at 17. This dynamotor has a motor end 18 and a generator end 19. The plate voltage is supplied from this generator 19 to the plates of the tubes 10 and 11 in a well known manner.

The voltage for operating the motor 18 and for energizing the filaments 12 of the vacuum tubes 10 and 11 is supplied by a storage battery shown diagrammatically at 20. The flow of current from this battery 20 is controlled by the starting switch 21. The fixed resistor 22 is supplied for reducing the voltage from the storage battery 20, whenever necessary, to the exact amount required for properly operating the filaments 12 of the vacuum tubes 10 and 11.

The operation of this transmitter and the means employed for overcoming its normal "chirping" tendencies will be understood from the following description.

The first step required to start the operation of the transmitter is to close the starting switch 21. This effects a flow of current from the storage battery 20 that starts the dynamotor 17 and at the same time supplies voltage to the filaments 12 of the vacuum tubes 10 and 11. The current supplied to the filaments 12 from the battery 20 flows through the fixed resistor 22 and through the variable resistor 13. At this point the telegraph key 16 is in the up or open circuit position. The keying relay 15 is therefore not energized and the make and break switch 14 is in an open position. The shunt path around the variable resistor 13 is therefore open circuited so that the entire current supplied to the filaments is compelled to flow through the variable resistor 13.

At this stage of the operation the grids of the vacuum tubes 10 and 11 are biased to cut-off according to a conventional method, and therefore no plate current is being drawn by the trans-

35

40

45

50

55

mitter. Consequently, the input current to the dynamotor is relatively small.

If the telegraph key 16 is now depressed, the grid bias of the tubes 10 and 11 is changed to normal, resulting in a flow of normal operating plate current through these tubes. Simultaneously, the plate current load of the transmitter is thrown on the generator end 19 of the dynamotor 17 and this in turn causes a sudden rise in the 10 input current to the motor end 18 of the dynamotor. This increase in current drain from the storage battery 20 causes the voltage at the terminals of the battery to drop and also causes additional RI drop in the lines between the battery 15 and the dynamotor 17. Since the transmitter is located near the dynamotor this voltage drop is also experienced at the filaments of the transmitter vacuum tubes 10 and 11.

The several operations described just above resulting from pressing the telegraph key occur the instant the key is closed. During a relatively short time interval, such as for example, that required to transmit a dash signal, i. e., 60 milliseconds, there are two operations that take place 25 more or less linearly with respect to time and which normally cause the emitted signal to chirp. They are as follows:

1. The dynamotor armature slows down due to added secondary load and reduced voltage at its 30 input terminals.

2. The temperature of the vacuum tube filaments decreases due to the reduced voltage at their terminals.

In view of the fact that the frequency of the 35 master oscillator 10 is effected both by filament temperature and plate voltage, it will be seen from the above description that the emitted frequency will be different at the beginning and end of a transmitted signal such as, for example, a dash. 40 In actual practice the reduction of filament and plate voltage both effect an increase in the frequency of the signal transmitted.

One of the principal features of my invention 45 as applied to the specific embodiment shown in the drawing consists of connecting, in the manner shown, a variable resistor 13 in the filament circuit of the vacuum tubes 10 and 11. This variable resistor serves as a compensating resistor as will appear from the following description. The 50 make and break switch 14, which may consist of a separate set of contacts on the keying relay 15, short circuits this compensating resistor 13 each time the telegraph key 16 is pressed. Now, if this 55 compensating resistor 13 is adjusted to give the same filament voltage when the telegraph key 16 is up and when it is depressed, the voltage applied to the filaments 12 of the vacuum tubes 10 and 11 will not vary during the operation of the tube. 60 Consequently, the temperature of the filaments 12 will remain constant. The "chirp" or frequency varying characteristic normally caused by varying filament voltage will accordingly be eliminated by means of this compensating resistor 13.

65 As mentioned above, however, some of the "chirp" in the transmitted signal is caused by the varying voltage supplied to the dynamotor, resulting in the latter slowing down under load conditions. Therefore, to eliminate the "chirp"

70 in the transmitted signal caused by variations in the dynamotor operation, the value of the compensating resistor 13 is increased so that the filament voltage actually rises a small amount when the telegraph key 16 is depressed. I have found 75 that by so regulating the value of this resistor 13

it compensates for the slowing down of the dynamotor armature. The reason for this is that when the voltage is raised the time rate of the filament temperature rise is approximately equal to the time rate of the armature speed decrease 5 and, since these two effects are working in opposite directions on the master-oscillator frequency, the result is a signal of substantially constant frequency which is audibly free of "chirp."

By means of the compensating filament resistor arrangement of my invention described 10 above, especially in connection with a master-oscillator power-amplifier type of radio telegraph transmitter, the signal emitted from the transmitter will be audibly free of chirp or frequency 15 variation. Also, the vacuum tube filament voltage is maintained at a constant value, which not only serves to eliminate chirp but also effectively increases the life of the vacuum tube filaments.

Various modifications of the system described 20 above will occur to those skilled in the art and are intended to come within the scope of my invention. For example, the compensating resistor 13 may be connected in the filament circuit of the master-oscillator tube alone so that the 25 control would be effected independent of the power amplifier. Any desired number of vacuum tubes of the oscillator and power amplifier type may be used. These tubes may employ a single grid or multiple grids. Also, the compensating filament resistor might be connected to the heater elements of cathode type vacuum tubes, although the control which compensates for the decrease of dynamotor speed could not be effected as efficiently as with the filament 35 type of tube.

Instead of a dynamotor any other type of 40 rotary power supply may be used, such as for example, a motor-generator. Thus, the primary source of power instead of being a storage battery might be an alternating current supply. When alternating current is used a motor-generator could be employed having an A. C. motor mechanically connected to a D. C. generator. In such a case the filaments of the vacuum tubes 45 could be heated through the intermediary of a suitable step-down transformer or from a suitable low voltage winding on the D. C. generator. The D. C. generator would also supply high voltage for the plates of the vacuum tubes.

The appended claims are addressed to some of the novel features of my invention.

I claim:

1. A radio transmitter comprising a vacuum tube having a filament, a rotatory power supply, 55 a source of power connected to said rotatory power supply for energizing the same, connection between said source of power and the filament of said vacuum tube for heating the same, a resistor connected between said source of power and said filament for compensating for the variations in power supplied to said filament and to said rotatory power supply during operation of said transmitter, and means for short circuiting and electrically disconnecting said variable resistor 60 during certain stages in the operation of the transmitter, whereby the frequency of relatively short signals emitted from said transmitter remains constant.

2. A radio transmitter comprising a vacuum 70 tube having a filament, a rotatory power supply, a source of power connected to said rotatory power supply for energizing the same, connection between said source of power and the filament of said vacuum tube for heating the same, a variable 75

- resistor connected between said source of power and said filament for compensating for the power variations in said transmitter during operation thereof, and means for short circuiting and electrically disconnecting said variable resistor during certain stages in the operation of the transmitter whereby the frequency of relatively short signals emitted from said transmitter remains constant.
- 10 3. A radio telegraphic transmitter comprising a vacuum tube having a filament, a motor generator, a source of power connected to said motor generator for energizing the same, connection between said source of power and the filament of said vacuum tube for heating the same, a variable resistor connected between said source of power and said filament for compensating for the supply voltage variations to said transmitter during operation thereof, and a keying relay for short circuiting and electrically disconnecting said variable resistor during certain stages in the operation of said transmitter, whereby the frequency of relatively short signals emitted from said transmitter remains constant.
- 15 4. A radio telegraphic transmitter comprising a vacuum tube having a filament, a dynamotor, a source of power connected to said dynamotor for energizing the same, connection between said source of power and the filament of said vacuum tube for heating the same, a variable resistor connected between said source of power and said filament for compensating for the supply voltage variations to said transmitter during operation

thereof, a keying relay for short circuiting said variable resistor during certain stages in the operation of said transmitter, and a telegraph key for alternately energizing and de-energizing said keying relay by which said variable resistor is 5 alternately electrically connected and disconnected in circuit between said power supply and said filament whereby the frequency of relatively short signals emitted from said transmitter remains constant.

10 5. A method for maintaining substantially constant the frequency output of a telegraphic vacuum tube transmitter during time intervals of dots and dashes, comprising decreasing the electrical resistance in the filament circuit of the 15 transmitter to compensate for the voltage drop in the filament supply circuit caused by increased current drain in that circuit during the transmission of dots and dashes.

20 6. A radio telegraphic transmitter comprising a vacuum tube, a source of power for furnishing filament voltage to said tube, a resistor connected in circuit between said source of power and the filament of said tube, and a second source of power for furnishing plate voltage to said tube, 25 and means responsive to operation of the transmitter for short circuiting said resistor to reduce the resistance in said circuit to compensate for drop in the filament and plate voltages applied to the tube during transmission of dots and 30 dashes.
